UNITED STATES PATENT OFFICE.

ERNEST SRNEC, OF BALTIMORE, MARYLAND.

ROTARY ENGINE.

No. 877,872.

Specification of Letters Patent.

Patented Jan. 28, 1908.

Application filed May 15, 1907. Serial No. 373,795.

To all whom it may concern:

Be it known that I, ERNEST SRNEC, of Baltimore, in the State of Maryland, have invented certain new and useful Improvements 5 in Rotary Engines; and I hereby declare that the following is a full, clear, and exact description thereof, reference being had to the accompanying drawings, which form part of this specification.

10 This invention is an improvement in rotary engines of the direct acting type in which rotary abutments are eccentrically mounted to rotate within the working chambers of the engine.

15 In the present invention I employ two or more high pressure working chambers and have rotating abutments in each chamber, the abutments being set at different angles in the several chambers so that there can be 20 no possibility of dead-centering the engine. Each working chamber communicates with a common steam-inlet chamber and a common outlet chamber so that live steam is admitted to both working chambers.

25 I further provide novel inlet and outlet valves which are so constructed and arranged relatively to the steam chambers that when steam is cut off from the engine by such valves, the steam chambers will be put into 30 communication so that the engine can run idly and by momentum, without shock, the confined steam being short circuited between the steam chambers. And furthermore the valves are so arranged that by a partial rotation 35 thereof the engine can be reversed, the exhaust chambers then becoming the inlet chambers, and the inlet chambers becoming the exhaust chambers. I have also provided ample means for lubricating all the moving 40 parts, so that friction in the engine will be reduced to the minimum, and I have also provided novel valve mechanism, whereby the speed of the engine may be easily controlled under varying loads.

45 The invention consists in the novel construction and combination of parts set forth in the appended claims, and will be fully understood from the following description in connection with the accompanying drawings, 50 in which—

Figure 1 is an end elevation of the engine. Fig. 2 is a side elevation thereof, partly broken away, showing interior parts. Fig. 3 is a vertical section through the engine. 55 Fig. 4 is a detail showing one of the shaft bearings. Fig. 5 is a transverse sectional

view through the main valve and connections. Fig. 6 is a detail view of such valves. Fig. 7 is a perspective view of one of the sliding abutments. Fig. 8 is a sectional view 60 of such abutments showing the lubricating channels. Fig. 9 is a sectional view through the rotary enlargements of the main shaft of the engine.

The casing 1 of the engine is preferably 65 cast with two internal working chambers 1^a which are approximately oval in form. Exterior to these working chambers 1^a and within the walls of the casing are formed steam chambers 1^b and 1ⁱ, respectively on 70 opposite sides of said working chambers—and the adjacent chambers 1^b at one side of the casing communicate through openings 1^c in the partition therebetween; while the adjacent chambers 1ⁱ, at the opposite side of the 75 casing, communicate through openings 1^h in the partition therebetween.

Each chamber 1^b communicates at bottom through a port 1^d with the adjacent working chamber 1^a, and each chamber 1ⁱ communicates at bottom with adjacent working chamber 1^a through a port 1^e. Direct communication between the chambers 1^b and 1ⁱ through the working chambers is prevented 80 by the sliding abutments 2^a and enlargements 2 on the main shaft of the engine, in which said abutments are held and guided.

The main shaft of the engine extends 85 through both working chambers and is journaled in suitable bearings 1° and 1^p at the 90 ends of the casing. A bearing 1^q (see Fig. 4) may be placed outside of the main fly wheel of the engine, if the shaft is elongated. It is not necessary, however, to have this third bearing 1^q in all cases. The main 95 shaft is located eccentrically of the working chambers and is provided therein with enlargements 2, which enlargements have a close fit against the packings 1ⁿ in the bottoms of the working chambers; thus the enlargements form a division between ports 1^d 100 and 1^e.

Direct flow of steam between ports 1^d and 1^e around enlargements 2 of the shaft is prevented by means of the sliding abutments 105 or pistons 2^a. These abutments extend through diametrically opposite openings 2^z in the enlargement 2 in each working chamber, the openings in the respective enlargements being formed at different angles, as 110 shown, so that the abutments 2^a in the respective working chambers extend at right

angles to each other. The abutments 2^a are of a length exactly equal to the diameter of the working chamber on any line which is drawn diametrically through the axis of the 5 shaft, consequently in any position of the shaft the ends of the abutment in each working chamber will contact with diametrically opposite sides of such chamber, and thus one end of each abutment will always form a 10 working piston against which the live steam entering the working chamber 1^a will act so as to rotate the abutments and the main shaft within the working chambers. The abutments 2^a are so arranged that live steam 15 will be always acting effectively there-against at one side or the other of the shaft, while exhaust steam is always escaping from the other side of such abutment, but at no time will there be direct communication be- 20 tween the inlet and the outlet ports. Prefer-ably the abutments are packed as shown at 2^c, and they are provided with internal oil passages, as shown at 2^v and 2^w, Figs. 7 and 8, through which lubricant is conducted to 25 the sides, and the ends of the abutments are provided with a suitable packing, as indicated at 2^d, and with frictional rollers 2^e which maintain close but comparatively frictionless joints between the abutments 30 and the walls of the working chambers.

Lubricating oil can be supplied to these abutments through passages 2^t in the enlargements 2 which passages communicate by suitable grooves 2^q with an annular channel 2^p in the enlargement 2 intermediate the abutments, to which channel oil is supplied from a duct 1^z in the partition between the working chambers, and said duct is connected through a tubular shaft 3^g, hereinafter referred to, with an oil supply 3^z, as indicated in the drawings. Oil can also be supplied to the bearings of the shafts through the passages 2^s, as indicated in Figs. 2 and 9.

Above the working chambers and intermediate the upper ends of chambers 1^b and 1^h are located the main valves 3 and 3^e which are constructed substantially alike. Valve 3 is the inlet valve and valve 3^e the outlet valve. The valve 3 (see Fig. 3) is 45 provided with two communicating ports 3^a and 3^b arranged about 120 degrees apart so that when the valve is in the position shown in Fig. 3, port 3^b will communicate with the steam inlet chamber 3^x, and port 3^a will 50 communicate with the chambers 1^b. The outlet valve 3^e is constructed similarly to valve 3 but is set oppositely thereto so that when valve 3 is in the position shown in Fig. 3, valve 3^e will be turned so that one 55 of its ports will communicate with one of the chambers 1ⁱ, and the other port will communicate with the exhaust chamber 3^y (see Figs. 2 and 5), consequently in this position, if steam is admitted to inlet chamber 3^x it 60 will flow through valve 3 and steam cham- 65

bers 1^b and port 1^d into the working chambers 1^a, driving the abutments and turning the shaft 2 to the right, and escaping from the working chambers into steam chambers 1ⁱ and thence through outlet valve 3^e to the 70 exhaust chamber 3^y. The course of the steam when the valves are in the position described, is indicated by dotted lines in the drawings. The valves 3, 3^e are provided on their inner ends with bevel gears 3^c and 3^h, 75 respectively, which mesh with opposite sets of similar bevel pinions 3^d strung on the tubular shaft 3^g which is arranged diametrically of the axes of the valves 3 and 3^e and intermediate the same, so that when one valve is turned in one direction the gearing will cause the other valve to move in the opposite direction to a similar extent. As shown, the shaft 3^g is tubular and its bore forms a duct for carrying lubricant from the 80 supply 3^z to the duct 1^z, see Fig. 5.

The valves may be axially connected by a shaft 3^f which may have a central enlargement 3ⁱ, as shown, and through which enlargement the shaft 3^g passes. The valves 85 are preferably tapered and may be fitted closely to their seats and may be adjusted thereto by means of nuts and washers on the ends of rods 3^r as shown in Fig. 5.

One of the valves, preferably the inlet 90 valve, is provided with a hand-wheel 3^m by which it can be turned (see Figs. 1 and 2) and it may be provided with an index finger 3^p and index 3^q as shown in Fig. 1, so that the operator can easily determine the position of the valve. 100

As the valves are turned to "closed" position, the ports 3^a and 3^b in the valves will establish communication between the upper ends of steam chambers 1^b and 1ⁱ so that the 105 steam which is trapped in the casing and working chambers can be circulated around therein by the abutments without any undue compression or shock.

If it is desired to reverse the engine the 110 valves are turned in the other direction until the port 3^a in inlet valve 3 communicates with the steam chamber 3^x and the port 3^b in valve communicates with the chambers 1ⁱ, simultaneously the exhaust valve 3^e is 115 shifted so that it establishes communication between steam chambers 1^b and exhaust 3^y. Therefore the passage of the steam through the casing and working chambers is changed 120 in direction and the abutments and rotary shaft will be driven to the left. By this simple but effective arrangement of valves the engine is perfectly under control at all times; when the steam is cut off it can run idly without shock; and it can be readily 125 reversed by simply turning the main valve about one-third of a revolution.

I have indicated in the drawings a means for governing the supply of steam, comprising a main steam valve 4 rotatably con- 130

nected to a stem 4^a which has a threaded engagement with a hand-wheel 4ⁿ (see Fig. 3) on which is a sprocket wheel 4^b which is connected by a chain 4^c to a smaller sprocket 4^d 5 on a shaft 4^e of the governing device (see Fig. 1). This shaft 4^e has a bevel gear 4^f which is capable of being meshed with either gear 4^g or 4^h on the governor spindle, which spindle is connected to an ordinary centrifugal governor 4ⁱ, by which the gears 4^g 10 or 4^h are thrown into or out of mesh with the gear 4^f according to the speed of the rotation of the governor spindle. The governor spindle carries a gear 4^k which is adapted to be meshed with either bevel gear 15 5^a or 5^b, sliding on a shaft 5, which is provided with a pulley 5^e adapted to be driven from a pulley 2^e on the main shaft of the engine.

Having described my invention what I claim as new and desire to secure by Letters Patent is:

1. In a rotary engine the combination of a casing, a plurality of adjacent working chambers therein, steam chambers on opposite sides of said working chambers, the steam chambers at each side communicating,—ports connecting the lower ends of said chambers with the working chambers, a main shaft extending through the chambers and located eccentrically thereof, an enlargement on said shaft within each chamber and intermediate the ports thereof, a sliding abutment in each chamber extending diametrically through said enlargement, and steam inlet and outlet valves for connecting the inlet with either steam chamber and connecting the outlet with the other chamber.

2. A rotary engine comprising a plurality of adjacent working chambers, a shaft extending through the chambers and provided with enlargements in each chamber, said enlargements having diametrical slots, sliding abutments fitted in said slots, the abutments in adjacent chambers alternating in position, steam chambers on opposite sides of each working chamber, the steam chambers at the same side of the engine communicating with each other, and the opposite steam chambers communicating with the intermediate working chambers at opposite sides of the rotary enlargements; with steam inlet and steam outlet valve mechanism whereby steam is admitted to one set of steam chambers and exhausted through the other set of steam chambers.

3. In a rotary engine the combination of a working chamber, a main shaft extending therethrough and located eccentrically thereof and provided with an enlargement in said chamber, a sliding abutment extending diametrically through said enlargement, and a steam chamber at each side of the working chamber, said steam chambers communicat-

ing with the working chamber at its lower end and at opposite sides of said enlargement; with a rotatable valve interposed between the upper ends of said chambers and provided with ports whereby when the valve is in one position communication is established between said chambers, and whereby when the valve is in other positions the ports may be set to communicate with one chamber while the other is cut off.

4. In a rotary steam engine the combination of a plurality of working chambers, rotary abutments in each working chamber formed at different angles, steam chambers on opposite sides of the working chambers, the sides of the working chambers respectively communicating therewith on opposite sides of the abutments, a steam inlet chamber, and an outlet chamber; with an inlet valve having ports whereby the valve may be caused to establish communication between the inlet chamber and either steam chamber, or to close the inlet and establish communication between both steam chambers; and an outlet valve adapted to establish communication between that steam chamber into which the steam is exhausted and the said outlet chambers, and means for simultaneously operating said valves.

5. In a rotary steam engine the combination of the working chambers and abutments therein, a steam inlet chamber, a steam outlet chamber, and opposite steam chambers communicating with the working chambers; with a pair of rotary valves respectively interposed between the inlet and outlet chambers and said steam chambers, and provided with ports whereby the inlet valve may be caused to establish communication between the inlet chamber and either steam chamber, and simultaneously the outlet valve caused to establish communication between the other steam chamber and the exhaust, and gearing for operating said valves simultaneously in opposite directions.

6. In a rotary steam engine, the combination of working chambers, rotary abutments therein, steam inlet and exhaust chambers, and steam chambers on opposite sides of the working chambers; with a pair of rotary valves respectively located between the inlet chamber and the steam chambers, and between the exhaust chamber and the steam chambers; and gears on the inner ends of said valve and intermediate pinions meshing with both gears whereby one valve is turned in one direction the other valve is similarly moved in the opposite direction, substantially as described.

7. In a rotary steam engine the combination of a plurality of working chambers, a rotary abutment therein, steam chambers on opposite sides of the working chamber, the sides of the working chambers respectively

- communicating therewith on opposite sides of the abutments, a steam inlet chamber, and a steam outlet; with a pair of rotary valves respectively located between the 5 inlet and the steam chambers, and between the outlet and the steam chambers, and gears on the inner end of said valve and intermediate pinions meshing with both gears whereby one valve is turned in one direction 10 the other valve is similarly moved in the opposite direction, substantially as described.
8. In a rotary engine the combination of a casing having a working chamber, a main shaft extending through said chamber and 15 located eccentrically thereof, and having a transverse slot for a sliding abutment, an annular oil channel beside said slot and oil passages leading from said channel to said slot; with a sliding abutment fitted in said 20 slot and provided with interior oil ducts adapted to receive oil from the ducts in the enlargement, substantially as described.
9. In a rotary engine the combination of a casing, a pair of working chambers therein, a main shaft extending through said chambers and located eccentrically thereof, and having 25 diametrical slots for sliding abutments, an annular oil channel between said slots, and oil passages leading from said channels to 30 said slots; with an oil duct in the wall of the casing to supply oil to said channel, and sliding abutments fitted in said slots and provided with interior oil ducts adapted to receive oil from the ducts in the enlargements, 35 substantially as described.
10. In a rotary engine the combination of adjacent working chambers, rotary abutments therein, steam chambers on opposite sides of the working chambers, a pair of 40 oppositely movable rotary valves above the

working chambers, and separating the said steam chambers, and means for simultaneously turning said valves in opposite directions, said valves being provided with ports, and adapted to be shifted to direct steam into either set of side chambers, and simultaneously exhaust it from the other set of side-chambers, or shifted to establish communication between the steam chambers outside the working chambers, substantially as described. 45

11. In a rotary engine the combination of adjacent working chambers, rotary abutments therein respectively communicating with the working chambers on opposite sides 55 of the abutments therein, steam chambers on opposite sides of each working chamber, the adjacent steam chambers at each side of the working chambers also communicating; a pair of oppositely movable rotary valves above the working chambers and separating the said steam chambers, said valves being provided with connected ports about one hundred and twenty degrees apart, and means for simultaneously operating said 60 valves in opposite directions, whereby the valves may be set so as to direct steam into either set of side-chambers, and simultaneously exhaust it from the other set of side-chambers; and whereby the valves can be 65 set to establish communication between the side steam chambers outside the working chambers, substantially as described.

In testimony that I claim the foregoing as my own, I affix my signature in presence of 70 two witnesses.

ERNEST SRNEC.
